UNITED STATES PATENT OFFICE.

RYSZARD KISZA, OF CHICAGO, ILLINOIS.

ASH-SIFTER.

1,283,528.

Specification of Letters Patent.

Patented Nov. 5, 1918.

Application filed April 24, 1918. Serial No. 230,437.

To all whom it may concern:

Be it known that I, RYSZARD KISZA, a subject of the Emperor of Austria, having declared my intentions to become a citizen of the United States of America, residing at Chicago, in the county of Cook and State of Illinois, have invented certain new and useful Improvements in Ash-Sifters, of which the following is a specification.

10 The primary object of the invention is the provision of a household article in the nature of an ash sifter whereby ashes may be easily and quickly sifted without the escape of dust or foreign particles while the 15 coal and cinders are separated for reburning.

A further object of the invention is to provide a device in which ashes may be sifted in the house in a cleanly and sanitary manner, the separated ashes and combustible material being automatically positioned for removal whenever desired.

A still further object of the invention is the provision of a sifting means adapted for depositing the finer particles passing there-through into a position for ready removal while provision is also made for readily removing the valuable material still remaining in the sifting means.

In the drawings forming a part of this 30 application and in which like numerals refer to corresponding parts throughout the several views:—

Figure 1 is a vertical transverse sectional view taken through the device with the refuse-receiving tray indicated by dotted lines in both its projected and its dumping position;

Fig. 2 is a front elevation of the lower portion of the device;

40 Fig. 3 is a longitudinal vertical sectional view taken upon line III—III of Fig. 1;

Fig. 4 is an enlarged detail view of a portion of the tray-mounting means taken upon line IV—IV of Fig. 1; and

45 Fig. 5 is a perspective view of the tray-mounting rod detached.

My device is capable of sifting many different kinds of material but is especially adapted for sifting ashes without creating

50 the usual dust and dirt incident to the ash-sifting operation.

I provide a casing 10 in the form of a cabinet having a hinged lid 11 at the top thereof while a cylindrical sieve or sifter 12 is rotarily mounted longitudinally of the 55 casing 10 by means of a shaft 13 journaled through the casing and provided with a turn-crank 14 at one side of the casing. The sifter 12 has a hinged section or cover portion 15 provided with a handle or knob 60 41 whereby said cover portion may be opened when the lid 11 is elevated for receiving the ashes mixed with coal and cinders into the sifter 12.

A rod 16 is positioned horizontally centrally 65 of the casing 10 in a plane transverse to the plane of the shaft 13, the said rod being secured in position by means of a disk 17 at the inner end thereof being secured to the rear wall 18 of the casing 10. A radially projecting finger 19 is carried by the rod 16 secured to the front wall 20 of the casing with the said rod 16 projecting centrally through a perforation 21 in the wall 20 and provided with a head or strap 22 upon its outer 75 free end.

A box-shaped tray 23 is provided for receiving the refuse or waste material from the sifter 12, said tray being slidably mounted in a horizontal position upon opposite 80 ledges 24 within the casing and being provided with a hand-receiving strap 25 at the front of the device. A coil spring 26 is attached to the casing wall 18 and bears against the rear or inner end 27 of the tray 85 23 for automatically projecting said tray to its open position upon releasing a swinging latch 28 carried by the front wall 20 and positioned within the opening path of movement of the tray 23 when the said latch 90 is in its depending position as shown in Fig. 2 of the drawings.

A hanger or bracket 29 is carried by the inner end 27 of the tray 23 having a split ring portion 30 slidably mounted upon the 95 rod 16. The opening 31 in the split ring 30 permits the hanger 29 to pass by the finger 19 as the opening 31 will accommodate the reduced or neck portion 32 of the finger 19 while a slot 33 in the wall 20 communicates with the perforation 21 and permits the hanger 29 to pass through said front 100

wall. In this manner, the tray may be slidably moved entirely outwardly of the casing 10 by the springs 26 which automatically project the tray 23 upon releasing the latch 28. By grasping the strap 25 the tray may be guided during its outward path of movement until the hanger 29 engages the strap head 22 as indicated by dotted lines in Fig. 1. The tray 23 may then be readily revolved upon the rod 16 for dumping the waste material into any desired receptacle, not shown, to be thrown away, the inverted position of the tray 23 being also indicated by dotted lines in Fig. 1.

15 A sliding drawer 34 is positioned upon the bottom 35 of the casing 10 for receiving the partially burned coal and cinders as well as other material which is left in the sifter 12 after the sifting operation, it being understood that the cover portion 15 is opened and the sifter 12 partially revolved for dumping the contents thereof into the drawer 34 when the tray 23 is in its open position.

25 A swinging latch 36 is carried by the casing wall 20 for retaining the drawer closed while upon releasing the latch 36, the coil springs 37 positioned within the casing 10 behind the drawer 34 will forwardly project the drawer outwardly of the casing. The drawer may be removed by means of the handhold 38 upon its forward end and carried away for dumping.

35 It will be apparent from the foregoing description of the construction and operation of the device that large quantities of ashes may be easily sifted by turning the crank 14 while the waste material passing through the sifter 12 is dumped from the tray 23 while the valuable material which it is desired to separate and save by means of the device is emptied from the sifter 12 into the drawer 34 and kept for future use. The entire device is preferably formed of 40 metal and it will be understood that the knob 41 is adapted for retaining the cover 15 closed during the rotation of the sifter 12 but is readily released for opening the cover when desired. An inclined guide or flange 45 39 is positioned within the casing 10 beneath the sifter 12 for guiding the material from the sifter into the tray 23, while the side walls of the tray 23 are preferably curved within the tray as at 40 for more easily 50 permitting the ashes to drop from the tray when the latter is inverted.

What I claim as new is:—

1. A device of the class described comprising a casing, a tray slidably mounted in the lower portion of the casing, the front wall of said casing having a perforation and an entrance slot therein, a rod secured through the casing above said tray extending centrally through said perforation, a hanger upon the rear end of the tray slid-

ably mounted upon said rod and adapted to pass through said perforation and slot during the outward opening movement of the tray, and a head upon the outer end of the rod adapted for engagement by said hanger when the tray is projected for rotation upon said rod to its inverted dumping position. 70

2. In combination with a casing, a tray slidably mounted in the lower portion of the casing for movement through the front 75 wall of the casing, said front wall being provided with a perforation and a slot leading therefrom at a point adjacent the path of movement of the tray, a rod secured within the casing above the tray projecting 80 outwardly of the casing centrally through said perforation, a mounting finger carried by the rod secured to the front wall of the casing having a reduced neck portion, a hanger upon the tray having a split ring portion 85 slidably mounted upon the rod, with the opening in the ring adapted for accommodating the neck of said finger during the outward movement of the tray and the passing of said hanger through said perforation 90 and slot, and a stop head for the tray upon the outer end of the rod adapted for engagement by the hanger when the tray is positioned exteriorly of the casing in its journaled relation upon the rod. 95

3. A device of the class described comprising a casing, a tray slidably mounted in the lower portion of the casing, the front wall of said casing having a perforation and an entrance slot therein, a rod secured 100 through the casing above said tray extending centrally through said perforation, a hanger upon the rear end of the tray slidably mounted upon said rod and adapted to pass through said perforation and slot during the outward opening movement of the tray, a head upon the outer end of the rod adapted for engagement by said hanger when the tray is projected for rotation upon said rod to its inverted dumping position, 105 automatic opening springs for the tray, a latch adapted for maintaining the tray in its normal closed position within the casing with said springs compressed. 110

4. In combination with a casing, a tray 115 slidably mounted in the lower portion of the casing for movement through the front wall of the casing, said front wall being provided with a perforation and a slot leading therefrom at a point adjacent the path of 120 movement of the tray, a rod secured within the casing above the tray projecting outwardly of the casing centrally through said perforation, a mounting finger carried by the rod secured to the front wall of the casing 125 having a reduced neck portion, a hanger upon the tray having a split ring portion slidably mounted upon the rod, with the opening in the ring adapted for accommodating the neck of said finger during the 130

outward movement of the tray and the passing of said hanger through said perforation and slot, a stop head for the tray upon the outer end of the rod adapted for engagement by the hanger when the tray is positioned exteriorly of the casing in its journaled relation upon the rod, automatic open-

ing springs for the tray, a latch adapted for maintaining the tray in its normal closed position within the casing with said springs compressed. 10

In testimony whereof I affix my signature.

RYSZARD KISZA.
